Inventor,
Harry Sidney Wood,
By - B. Augur, Atty.

UNITED STATES PATENT OFFICE.

HARRY SIDNEY WOOD, OF LONDON, ENGLAND.

POCKET LOCK.

Application filed February 3, 1921. Serial No. 443,398.

To all whom it may concern:

Be it known that I, HARRY SIDNEY Wood, a subject of the King of Great Britain and Ireland, residing at London, England, have 5 invented new and useful Improvements in Pocket Locks, of which the following is a specification.

This invention relates to locks for pockets, bags and similar receptacles and the object 10 of the present improvements is to provide a device which can be readily applied to any pocket of a coat or waistcoat for example or to a bag particularly to bags provided with an outer flap pocket, which effectively 15 locks the pocket and is concealed from view and can only be unlocked by pressure on a particular spot known to the wearer.

With the above objects in view a device 20 constructed in accordance with my invention consists of two parts, a stud for attachment to the pocket of a coat or other garment and a holder, which may conveniently be stamped out of sheet metal and is attached to the body of the garment the aforesaid 25 stud being adapted to engage with the holder and is securely held there in such a manner that it can only be released therefrom by pressure applied to a stud carried by the holder.

30 But in order that my invention may be more clearly understood I have illustrated a device constructed in accordance therewith in the accompanying drawing, Figures 1, 2 and 3 being front, rear and side elevations 35 respectively of the holder and Figures 4 and 5 side and front elevations respectively of the stud.

Figures 6 and 7 shew the application of 40 my invention to an ordinary pocket and a pocket provided with a flap respectively.

Similar letters of reference relate to corresponding parts in all the figures of the drawing on reference to which and particularly to Figures 1 to 3 thereof it will be 45 appreciated that the holder comprises a strip of sheet metal *a* with an aperture *b* provided with a bell mouth *c* through which the head *d* and shank *e* of the stud *f* (Figures 4 and 5) are passed for engagement of the stud *f* 50 with the holder *a*, to the rear face of which is riveted, or otherwise secured, the spring *g* formed of wire of the shape shewn clearly in Figure 2 and the ends of the legs *h* of which are slightly bowed to more or less coincide 55 with the aperture *b* and provide a resilient

locking means *i* for the stud *f*. This stud is preferably formed with a flat shank *e* (Figure 5) to prevent catching of the same, when ejected, in the edge of the hole *b* and the base *j* is provided with the holes *k* for 60 attachment of the stud by sewing or otherwise. To the rear face of the holder *a* and behind the spring *g* is arranged the blade spring *l* riveted or otherwise secured to the cross piece *m*, which not only bears against 65 the head *d* of the stud *f* when the same is engaged by the locking spring *i* and keeps the same in position but also when the stud is released acts as an ejection spring to eject the same. The releasing stud *n* which projects from the front face of the holder *a* and is kept in its normal position by the blade 70 spring *o*, attached to the holder *a* by rivets or otherwise is provided with a wedge shaped shank *p* the end of which normally 75 engages between the legs *h* of the spring *i*; on pressure being applied to the stud *n*, against the action of the spring *o*, the shank *p* owing to its wedge shape separates the legs *h* of the spring *i* and so releases the head 80 *d* of the stud *f* engaged thereby.

The operation of the device will be readily understood from the above detailed description.

The holder *a* is inserted in and attached 85 by sewing or otherwise, being provided for this purpose with the holes *r*, to the body of the coat or waistcoat for example and the stud *f* to the pocket *A* as shewn in Figure 6. In the case of a flap pocket either of a coat or bag as shewn in Figure 7 the holder *a* is inserted in the pocket *b* and the stud *f* in the flap *C*; the operation in both cases being the same. The garment will be provided in practice with the required opening to enable the stud member to enter the socket of the holder. To lock the pocket the head *d* and shank *e* of the stud *f* are passed through the aperture *b* and pressed against the blade spring *l* which 100 yields and allows the engagement of the head *d* by the bow shaped ends *i* of the legs *h* of the spring *g*. To unlock the pocket it is merely necessary to press the releasing stud *n*, which operates in the 105 manner previously described, and is concealed from view while perceptible to the touch of the wearer of the garment in which the device is inserted.

Obviously if any attempt is made to un- 110

lock the pocket by an unauthorized person the wearer is warned of the fact by feeling the pressure which is necessary to operate the releasing stud.

- 5 The device is equally effective when the coat is unbuttoned or open or even carried on the arm as in this case it would require two hands to open the pocket one on the inside thereof and the other on the outside
10 to operate the releasing stud.

What I claim and desire to secure by Letters Patent is:—

1. A pocket lock comprising a stud for attachment to the pocket of a garment, a
15 plate for attachment to the body of the garment and provided, near one end with an opening for the reception of said stud, spring acting securing means mounted on said plate to engage said stud, a second stud
20 having means to release said securing means from the first-named stud when said second stud is moved in one direction, said second stud being spaced from said opening and arranged near the opposite end of said plate,
25 and a spring attached to said plate and said second stud, and holding said second

stud in projected position, disengaged from said spring acting securing means.

2. A pocket lock comprising a stud for attachment to the pocket of a garment, a 30 plate for attachment to the body of the garment and provided, near one end with an opening for the reception of said stud, spring acting securing means mounted on the rear side of said plate to engage said 35 stud, a second stud having means to release said securing means from the first-named stud when said second stud is moved in one direction, said second stud being spaced from said opening and arranged near the 40 opposite end of said plate, a spring attached to said plate and said second stud, and holding said second stud in projected position, disengaged from said spring acting securing means, and a spring, also on the rear 45 side of said plate, arranged in the path of the first-named stud, and active, when said stud is released by the securing means, to eject the said stud from said opening.

In testimony whereof I have signed my 50 name to this specification.

HARRY SIDNEY WOOD.
